UNITED STATES PATENT OFFICE.

CHARLES FRANCIS JENKINS, OF WASHINGTON, DISTRICT OF COLUMBIA.

AEROPLANE OR FLYING-MACHINE.

1,092,365.

Specification of Letters Patent. Patented Apr. 7, 1914.

Application filed April 20, 1910. Serial No. 556,514.

To all whom it may concern:

Be it known that I, CHARLES FRANCIS JENKINS, citizen of the United States, residing at Washington, District of Columbia, have invented certain new and useful Improvements in Aeroplanes or Flying-Machines, of which the following is a specification.

This invention relates to that class of machines known as aeroplanes, and has for its main objects a construction which is easily manageable and at the same time has supporting surfaces so disposed as to give a greater degree of stability than is found in other forms more common.

According to a law of aerodynamics, now quite commonly known as the Langley law, the power required to support a given weight with a given supporting surface falls off rapidly as the speed increases. Obviously it is also true that if the speed decreases greater supporting surface is required to carry a given weight. As starting is a gradual acceleration from nothing to self-supporting speed, it is evident that a larger supporting surface will get up sooner than a smaller one, other things being equal. It is also true that a more gentle landing can be made, for the same reason, with machines having a supporting surface of greater area. In all classes of mechanically, self-propelled and self-steering machines (meaning, a machine steered by agencies aboard itself) the longer the machine, the farther apart the supporting members, the more reliable its stability at increased speeds. This latter principle is also given due weight in the present invention by lengthening the framing until the machine is considerably longer than it is wide. These, then, are the principal objects of this invention; *i. e.*, (1) a flying machine which is self-supporting at moderate speeds, and (2) one which will be least disturbed by gusts of wind.

Other minor objects are, the improved means for steering, both vertically and horizontally.

In the drawings accompanying these specifications Figure 1 is a side elevation of the machine, Fig. 2 a top view, Fig. 3 an end view of the machine, Fig. 4 an end view of the front planes, and Fig. 5 a top view of the driving mechanism.

In all the drawings like symbols refer to like parts, A being the front upper and A' the front lower supporting plane; B the

upper and B' the lower rear supporting plane; C the supporting bridge-braced framing between the front and the rear planes. On this bridge-framing are suitably mounted propellers D and D' one on each side. These are driven by the motor E also mounted on the framing. The motor drives the propellers through the motor shaft F and the propeller shafts G and G', the motor shaft communicating rotary motion to the propeller shafts by means of the friction wheels H, I and I'. The position of these three wheels with relation to each other is governed by means of the lever K and the connecting rods L' and L. This lever is in turn movably held by the worm M and rack-sector N through the medium of the steering shaft O and the handwheel P, the latter located in convenient reach of the operator who sits on the bench Q. To the lever K, each side of and equi-distant from the fulcrum K², are fastened taut wires R and R' which pass through rings at S and S' respectively and attach to the rudder T hinged at U, that is, having its forward end free to move laterally. From this description it is obvious that rotation of the steering wheel shaft O will change the lever K, and, of a consequence, the relation of the driving wheels, in such a way, for example, as shown in Fig. 5, as to increase the speed of the left propeller and decrease the speed of the right propeller, which, of itself, would tend to turn the machine toward the right. This action is helped by the changed position of the rudder, which, in the illustration given, would cause the forward end of the rudder to swing over to the left catching the air on the right of the rudder tending to aid in turning the machine to the right. In case the motor stops accidentally or by the intention of the operator, while the machine is in motion, the steering is done wholly by the rear rudder.

The control of the machine in a vertical direction, to make it rise or fall, is accomplished by drawing back or pushing forward on the top plane which tips the front double plane as a whole to bring its under surfaces more or less obliquely against the wind. This is clearly illustrated in Fig. 4, in which the symbols A² and A³, shown by dotted lines, indicate a position which would cause the advancing machine to rise as against a position shown in full lines A and

A'. This drawing back of the upper part of the whole braced frame-work of the front planes is accomplished by means of the worm V working in the rack-sector W, the 5 worm being mounted on the shaft X. The shaft has secured thereto the steering wheel Y, also located in convenient reach of the operator. The hinge Z permits of this backward and forward movement of the upper 10 part of the forward planes. It would be possible to similarly hinge the rear planes, but it is believed that this is so obvious as not to need illustrating.

What I claim, is—

- 15 1. In devices of the class described, the combination with suitable supporting planes, of motor devices, two propellers driven by said devices, an approximately vertical rudder, and means for at will varying the relative speed of the propellers and simultane-

ously and correspondingly varying the position of the rudder.

2. In devices of the class described, the combination with a rotary power shaft and two transverse propeller shafts upon opposite sides of the power shaft, of variable speed gearing connecting the power shaft with each propeller shaft, a centrally pivoted lever arranged to vary the speed of the propeller shafts inversely as the lever swings 25 on its pivot, worm and gear devices for swinging and holding the lever, a vertical rudder, and means whereby the swinging of said lever adjusts the rudder.

In testimony whereof I have affixed my 35 signature in presence of two witnesses.

CHARLES FRANCIS JENKINS.
